G. HINMAN

DRILL PULLER

Filed Nov. 22, 1924.

UNITED STATES PATENT OFFICE.

GRANT HINMAN, OF CLARKDALE, ARIZONA.

DRILL PULLER.

Application filed November 22, 1924. Serial No. 751,649.

To all whom it may concern:

Be it known that I, GRANT HINMAN, a citizen of the United States, and a resident of Clarkdale, in the county of Yavapai and State of Arizona, have invented certain new and useful Improvements in Drill Pullers, of which the following is a specification.

My invention relates to and has for its purpose the provision of a device of extremely simple, inexpensive and durable construction, which is adapted to be applied to a drill rod employed in the drilling of holes in the earth, preparatory to blasting for pulling the drill when jammed, and in such manner as to utilize the rotational movement of the drill rod, thus eliminating the exercise of any manual effort in the pulling of the drill.

I will describe only one form of drill puller embodying my invention, and will then point out the novel features thereof in claims.

In the drawings,

Figure 1 is a view showing in vertical section and partly in elevation one form of drill puller embodying my invention;

Figure 2 is a fragmentary view taken at right angles to Figure 1;

Figure 3 is a horizontal sectional view taken on the line 3—3 of Figure 2;

Figure 4 is a fragmentary vertical sectional view of the puller, showing the gripping elements thereof in gripping position with respect to a drill rod.

Referring specifically to the drawings, in which similar reference characters refer to similar parts in each of the views, my invention in its present embodiment comprises a standard including a relatively wide and circular base 15, having a peripheral flange 16, the diameter of the base being sufficient to completely surround the well opening when applied to the surface of the ground. Extending upwardly from the base 15 is a tubular body 17 formed integral with the base and reinforced by webs 18 arranged at circumferentially spaced intervals and connected to the base 15. Between the webs, the tubular member 17 is formed with vent openings 19 through which dust may readily pass exteriorly of the standard.

The tubular body 17 constitutes one of the screw elements of the puller, and to this end it is interiorly screw threaded, as indicated at 20. The other screw element of the puller is a tubular member 21 exteriorly

threaded and telescopically received by the tubular body 17, as clearly illustrated in Figure 1, so that by rotation of the element 21 it can be adjusted vertically within the 60 standard.

The upper end of the screw element 21 is provided with a collar 22 having notches 23 therein arranged in pairs, with each pair receiving the ends of a substantially U-shaped gripping member 24, and in such manner as to allow pivotal swinging movement of the member to occupy a gripping position, as shown in solid lines in Figure 1, or non-gripping position as shown in dash lines. 70 In the present instance the puller is provided with two gripping members 24, and these members are adapted to co-operate with a clamp 25 in securing a drill rod 26 against rotative movement with respect to 75 the screw element 21. As shown in Figures 3 and 4, the gripping elements are formed with socketed jaws 26^a adapted to conform to the cross sectional contour of the drill rod 26, and these jaws are formed with ser- 80 rated surfaces 27, as clearly shown in Figure 4, so as to prevent vertical slippage of the drill rod. The clamp 25 is constructed to embrace the gripping members 24 and is provided with a set screw 28 which may be 85 adjusted to bring the clamp into clamping relation to the gripping elements and to thereby securely hold the latter in gripping position with respect to the drill rod.

In practice, the standard is arranged so 90 that its base is in surrounding relation to the ground opening, when the drill rod 26 can be passed downwardly therethrough into the earth. In the normal operation of the drill rod the gripping elements 24 oc- 95 cup non-gripping position so that the drill rod can rotate independently of the drill puller. However, should the drill for any reason become jammed in the hole so as to prevent further operation thereof, the pull- 100 ing of the drill can be readily effected by moving the gripping elements 24 to gripping position with respect to the drill rod and then securing the elements in gripping position by means of the clamp 25. Upon 105 continued rotation of the drill rod, rotative movement of the screw element 21 is now effected and in such direction that an up- 110 ward feeding of the same within the standard takes place, thereby exerting an upward pull upon the drill rod to effect a release of the drill.

Although I have herein shown and described only one form of drill puller embodying my invention, it is to be understood that various changes and modifications may be made herein without departing from the spirit of the invention and the spirit and scope of the appended claims.

I claim:

1. A drill puller comprising a stationary element, a rotatable element, coating means connecting the elements to cause vertical movement of the rotatable element when the latter is rotated on the stationary element, and means for securing a drill rod to the rotatable element so that when the drill rod is rotated, rotation of the rotatable element is effected, said means comprising identical gripping members pivoted on the rotatable element, and means removable from said members and adapted to force same into clamping engagement with said drill rod.

2. A drill puller comprising a stationary element, a movable element rotatable in the stationary element and having screw threaded engagement therewith to cause vertical movement of the movable element when rotated, and means for securing a drill rod to the movable element so that when the latter is rotated vertical movement of the drill rod is effected, said means comprising identical gripping members pivoted on the rotatable element, and means removable from said members and adapted to force same into clamping engagement with said drill rod.

3. A drill puller comprising tubular telescopic elements having screw threaded engagement with each other, gripping members carried by one of the elements, and a clamp for securing the gripping elements in gripping relation to a drill rod extending through the elements, the clamp being removable from the gripping members and said members being pivoted to the upper end of said one element so that they can be swung downwardly and outwardly to hang at the sides of said element when the clamp is removed.

4. A drill puller comprising a stationary tubular element, a movable tubular element telescopically received by the first element and having screw threaded engagement therewith to cause vertical movement of the movable element when rotated in the stationary element, gripping members pivoted on the movable element to occupy gripping or non-gripping positions with respect to a drill rod extending through the movable element, and a clamp engaging the gripping members for securing the latter in gripping position with respect to the drill rod, whereby the movable element and drill rod are rotatable as a unit, the gripping members being of identical U-shaped construction with their free ends constituting their pivoted points and mounted on the upper end of the movable element so as to cause the connecting portions of said members to straddle the drill rod.

5. A drill puller comprising telescopic elements having screw threaded engagement with each other, recesses formed in one of the elements, gripping members pivotally mounted in the recesses, said members being of substantially U-form and having socketed jaws with serrated surfaces, and a clamp releasably engaging the members for the purpose described.

6. A drill puller comprising a standard having a relatively broad base and a tubular body extending upwardly from the base, a tubular member telescopically received within the tubular body and having screw threaded engagement therewith, vent openings formed in the tubular member, reinforcing webs connecting the tubular body and base, recesses formed in the tubular member, gripping members pivotally mounted in the recesses and of substantially U-form, socketed jaws on the gripping members, and a clamp engaging the gripping members for securing the jaws in gripping position with respect to a drill rod extending through the tubular member.

GRANT HINMAN.
